CHARLES B. YOUNG, OF AURORA, AND GARTH G. GILPIN, OF RIVERSIDE, ILLINOIS.

DRAFT-YOKE FOR RAILWAY-CAR DRAFT-RIGGING.

1,177,003.

Specification of Letters Patent.

Patented Mar. 28, 1916.

Application filed May 5, 1914. Serial No. 836,448.

To all whom it may concern:

Be it known that we, CHARLES B. YOUNG and GARTH G. GILPIN, citizens of the United States, residing at Aurora, in the county of Kane and State of Illinois, and Riverside, in the county of Cook and State of Illinois, respectively, have invented a certain new and useful Improvement in Draft-Yokes for Railway-Car Draft-Rigging, of which the following is a full, clear, concise, and exact description, reference being had to the accompanying drawings, forming a part of this specification.

Our invention relates to improvements in draft yokes for railway car draft rigging.

The object of our invention is, to provide a draft yoke having means for readily detaching the same from, and engaging it to a draw bar.

In the drawings forming a part of this specification, Figure 1 is a plan view of a draft yoke and draw bar extension embodying our invention; Fig. 2 is a side elevation thereof; Fig. 3 is a central vertical longitudinal section of the forward end of the yoke and the draw bar extension, showing the butt of the draw bar in engagement with the draw bar extension; Fig. 4 is a cross section taken on line 4—4 of Fig. 2; Fig. 5 is a cross section taken on line 5—5 of Fig. 2.

Referring to the drawings, the numeral 6 indicates a draw bar, only the rear end thereof being shown in the drawing, having a butt 7, and provided with the usual vertical rivet hole 8. The draw bar is also provided with a transverse slot 9 to receive the coupler key 10.

The numeral 11 represents a draw bar extension comprising the shank 12 and the head 13. The head 13 contains a forwardly opening hollow recess 14 adapted to receive the draw bar. The rear wall of the recess 15 is preferably engaged by the rear face 16 of the draw bar's butt. The lateral walls 17—17 forming the said recess are provided with transverse slots 18—18 registering with the slot 9 in the draw bar, and receiving the coupler key 10. The upper and lower walls 19 and 20, respectively, forming the said recess 14 are provided with registering perforations 21—21 alined with the vertical rivet hole 8 in the draw bar to receive the bolt 22, which is provided at its upper end 23 with the head 23, and receives the nut 24 and the nut-lock 25 at its lower end. The

said bolt passes through a notch or opening 26 in the key 10, said opening or notch being preferably located on the rear edge of said key. The bolt 22 serves to prevent accidental displacement of the coupler key 10. At its rear end the draw bar extension is provided with a vertical, preferably round opening 27 to receive the preferably cylindrical vertical key 28 therethrough.

The draft yoke 29 comprises an upper limb 30, a lower limb 31, a rear, preferably integral connecting member between said limbs, and a preferably integral head 33 joining the two limbs together at their forward ends. A reinforcing median rib 34 extends longitudinally around the outer faces of the limbs 30 and 31 and connecting member 32 of the yoke, the said reinforcing rib being preferably integral with the said limbs and rear connecting member. The head 33 of the yoke has a forward opening 35 adapted to receive the shank 12 of the draw bar extension 11. The lateral walls 36—36 forming said opening are preferably integral with the limbs of the yoke, and are forwardly outwardly flared, as illustrated in Fig. 1 of the drawings, to permit lateral movement of the draw bar extension in reference to the yoke. The upper and lower limbs of the yoke are provided at their forward ends with the in-turned gibs 38—38 having preferably integral rearwardly extending spaced-apart lugs 39—39 between which are received the ends of the key 28. The lugs 39—39 form flanges on the inner faces of the limbs of the yoke, preferably mounted in line with the edges of a limb of the yoke and integral therewith.

In rearward movement of the draw bar, the draw bar extension is moved rearwardly to compress any suitable compression resisting member which may be mounted in the transverse opening 40 in the draft yoke. In such movement, the key 28 slides rearwardly in the slots formed between the members 39—39, and somewhat back of its extreme rearward movement. The lower limb of the yoke is provided with a vertical opening 41 adapted for the passage of the key 28. In connecting the draw bar extension 11 to the draft yoke, the said extension is inserted in the forward opening of the yoke and moved rearwardly until the vertical opening 27 therethrough registers with the opening 41 in the lower limb of the yoke, whereupon the key 28 is inserted into

position, and the draw bar extension drawn forwardly, drawing the key 28 into its operative position in the slots formed between the members 39-39. In disconnecting the 5 draw bar extension from the yoke, the draw bar extension is moved rearwardly until the key 28 registers with the opening 41 in the yoke, and if the key 28 does not readily drop through said opening, it may be forced 10 therethrough by means of a punch driven through the registering opening 42 in the upper limb 30 of the draft yoke. On forward movement of the draw bar, the yoke is drawn forwardly by the engagement of 15 the key 28 against the lugs 38-38 at the forward ends of the limbs of the yoke, and forming the forward end of the slots between the members 39-39.

We claim:

20 In a draft rigging for railway cars, in combination, a yoke, a coupler member and

a removable pin extending through said member, said yoke at its forward end having front vertical walls between which the rear end of said member is adapted to extend, the inner faces of the upper and lower walls of said yoke being longitudinally slotted to receive the ends of said pin, said pin in the normal position of the parts being retained at the forward ends of said 25 slots, said upper and lower walls of the yoke being provided also with aligned perforations located to the rear of the normal position of said pin, one of said recesses being sufficiently enlarged to permit the removal 30 of said pin therethrough.

CHARLES B. YOUNG.
GARTH G. GILPIN.
